TRANSFER TANK

James S. Sharpe, 1214 E. Palmdale,
Orange, Calif. 92665

Filed Nov. 1, 1971, Ser. No. 194,795

Term of patent 14 years

Int. Cl. D30—99

U.S. Cl. D30—99

FIG. 7.

FIG. 1 is an isometric view of a transfer tank, showing my new design with one of the two side doors in opened position;

FIG. 2 is a side elevational view with both doors closed;

FIG. 3 is an opposite side elevational view;

FIG. 4 is a top plan view with both doors closed;

FIG. 5 is a bottom plan view with both doors closed;

FIG. 6 is an end elevational view with both doors closed, the opposite end being substantially a mirror image thereof;

FIG. 7 is an enlarged transverse cross-sectional view taken at line 7—7 of FIG. 1.

I claim:

The ornamental design for a transfer tank, substantially as shown and described.
